(57) **CLAIM**

The ornamental design for the light bulb changer holder, as shown and described.

DESCRIPTION

FIG. 1 is a top perspective view of a light bulb changer holder in accordance with the present invention;

FIG. 2 is a front elevational view of the light bulb changer holder illustrated in FIG. 1;

FIG. 3 is a rear elevational of the light bulb changer holder illustrated in FIG. 1;

FIG. 4 is a right side elevational view of the light bulb changer holder illustrated in FIG. 1;

FIG. 5 is a left side elevational view of the light bulb changer holder illustrated in FIG. 1;

FIG. 6 is a top plan view of the light bulb changer holder illustrated in FIG. 1; and,

FIG. 7 is a bottom plan view of the light bulb changer holder illustrated in FIG. 1.

The broken lines depict portions of the light bulb changer holder in which the design is embodied that are not considered part of the claimed design.

1 Claim, 7 Drawing Sheets
